UNITED STATES PATENT OFFICE.

ELONA BROWN, OF JACKSONVILLE, FLORIDA.

BRASSIÈRE

Application filed August 4, 1921. Serial No. 489,802.

To all whom it may concern:

Be it known that I, ELONA BROWN, a citizen of the United States, residing at Jacksonville, in the county of Duval and State of Florida, have invented a new and useful 5 Brassière, of which the following is a specification.

The device forming the subject matter of this application is a brassière, and the invention aims to provide novel means for retracting or drawing inwardly, the lower edge of the brassière, the construction being such that the article will be peculiarly effective when worn by persons who are more or less 10 obese. The invention aims to provide means for controlling the lower edge of the brassière, as aforesaid, without preventing the brassière from adjusting itself longitudinally, to conform to the body of the wearer. 15 With the above and other objects in view, which will appear as the description proceeds, the invention resides in the combination and arrangement of parts and in the details of construction hereinafter described 20 and claimed, it being understood that, within the scope of what is claimed, changes in the precise embodiment of the invention shown can be made without departing from the spirit of the invention.

30 In the accompanying drawings:—

Figure 1 shows in plan, a device constructed in accordance with the invention; Figure 2 is a section on the line 2—2 of Figure 1.

35 In Figure 1 there is shown a brassière including a body 1 having arm straps 2 and a draw string 3, the ends of the body 1 being adapted to be united releasably by any suitable connection 4, the numeral 8 marking 40 any suitable device for connecting the lower edge of the brassière to a corset.

Any desired number of flexible elements 5 are secured at their upper ends to the lower edge portion of the body 1, the lower ends of 45 the flexible elements 5 being fashioned into guides or loops. The loops or guides at the ends of the body 1 are denoted by the numeral 6, the intermediate loops being design-

nated by the numeral 7. Through the loops or guides 6 and 7 extends a retractile member 9 which, preferably, is a piece of elastic. The member 9 is secured at 10 to the two terminal loops 6 but slides freely in the intermediate loops 7. The member 9 measured between the loops 6 preferably is 55 somewhat shorter than the lower edge of the body 1, measured between the same points, this fact being made manifest in Figure 1 by showing folds 11 in the body 1. On the ends of the retractile member 9 are 60 mounted connecting means of any desired sort, such as snap fasteners 12.

In practical operation, when the garment is in use, the retractile member 9 will draw inwardly, the lower portion of the body 1 of the brassière, with obviously desirable results. Since the loops 7 are slidably mounted on the retractile member 9, the brassière can adjust itself to the body of the wearer, longitudinally of the member 9. The snap 70 fasteners 12 or their equivalent, obviously provided for the necessary adjustments, so that the retractile member or elastic 9 will extend about the body of the wearer with a graduated or adjusted constricting effort. 75

What is claimed is:—

In a device of the class described, a brassière comprising a body; guides mounted on the lower edge of the body adjacent to the ends of the body; intermediate guides 80 mounted on the lower edge of the body and disposed between the first specified guides; a retractile member mounted in all of the guides and slideable in the intermediate guides; and means for securing the retractile 85 member to the first specified guides, the ends of the retractile member extending beyond the first specified guides, for connection with each other.

In testimony that I claim the foregoing as 90 my own, I have hereto affixed my signature in the presence of two witnesses.

ELONA BROWN.
